UNITED STATES PATENT OFFICE

168,266

OVERSHOE OR THE LIKE

Jacob S. Kamborian, West Newton, Mass.

Application May 10, 1951, Serial No. 15,125

Term of patent 14 years

(Cl. D7—4)

To all whom it may concern:

Be it known that I, Jacob S. Kamborian, a citizen of the United States of America, residing at West Newton, county of Middlesex, and Commonwealth of Massachusetts, have invented a new, original, and ornamental Design for an Overshoe or the like, of which the following is a specification, reference being had to the accompanying drawing, forming a part thereof.

Fig. 1 is a plan view of one side of the overshoe in flattened position, both sides being identical;

Fig. 2 is a perspective view of the overshoe in a slightly opened position.

I claim:

The ornamental design for an overshoe or the like, substantially as shown and described.

JACOB S. KAMBORIAN.
